UNITED STATES PATENT OFFICE.

HARRY T. WHITE, OF HIGHLAND PARK, MICHIGAN.

THREADING TOOL FOR AUTOMATIC MACHINES.

Application filed December 11, 1920. Serial No. 429,865.

To all whom it may concern:

Be it known that I, HARRY T. WHITE, a citizen of the United States of America, residing at Highland Park, in the county of Wayne and State of Michigan, have invented certain new and useful Improvements in Threading Tools for Automatic Machines, of which the following is a specification, reference being had therein to the accompanying drawings.

The invention relates to threading tools of that type in which the threading is effected by a series of chasers surrounding and concentric to the axis of the work which is rotated in relation thereto.

It is usual to mount the chasers in a head which is rotatable upon a shank carrying cams for actuating the chaser jaws inward and outward. A latch is provided for holding the head in a position on the shank where the chasers are closed in or in cutting position, and a spring is provided for rotating the head to expand the chaser jaws when the threading operation is completed. Also the rotary head is longitudinally movable upon the shank a sufficient distance to disengage from the latch when the cutting of the thread is completed, this being accomplished by the holding of the shank from movement while the head is still advanced upon the thread of the work.

The general organization of my improved tool is the same as with other tools of the type, but the present invention relates to certain improved features which add to the convenience and accuracy of the tool and simplify its manufacture. One of these features is the construction of the chasers or thread cutters and the manner of mounting the same. Another feature is the construction which permits of the introduction of the spring or springs for rotating the head after all the other parts have been assembled. Other features will be more specifically referred to hereinafter.

In the drawings:

Figure 1 is a sectional side elevation of the tool;

Figure 2 is an end elevation with parts omitted;

Figure 3 is a cross-section on line 3-3 of Figure 1;

Figure 4 is a longitudinal section on line 4-4 of Figure 3;

Figure 5 is a cross-section on line 5-5 of Figure 6; and

Figure 6 is a longitudinal section on line 6-6 of Figure 5;

Figure 7 is a longitudinal section on line 7-7 of Figure 8; and

Figure 8 is a cross-section on line 8-8 of Figure 7;

Figures 9 and 10 are views similar to Figures 1 and 2 showing a modified construction.

Figure 11 is a detail sectional view taken on the line 11-11 of Figure 2.

A is the shank of the tool which is adapted for mounting in the machine in alignment with the work to be threaded. B is a collar projecting radially outward from the shank, and C is a head which is sleeved upon the shank and has a limited longitudinal adjustment thereon. This head is formed of several annular members D, E and F, which are machined and fitted to each other. The member D fits about a portion of the shank A and is recessed on its rear side to receive the collar B. The member E also fits about a portion of the shank in front of the member D, and its forward portion is radially slotted to receive the chasers or thread cutters. The members D and E are rotatively fixed to each other and to the collar B by pins G which are preferably tightly fitted to the member D and slidably fitted in the collar B and member E. Shoulder screws H also connect the members D and E, the heads H' of which engage counterbores in the member E, while springs I sleeved upon the shanks of said screws abut with their opposite ends against the heads H' and the bottom of the counterbore. The arrangement is such that the members D and E are yieldably held in contact by the tension of the springs I, but are capable of longitudinal separation while maintaining their rotatively fixed relation.

The member F is sleeved upon the member D, but is held from longitudinal movement by a shouldered portion F', which retains it from movement in one direction, while a plate J holds it from movement in the opposite direction. The member E is provided with an outwardly-extending flange E' and between this flange and the member F is formed an annular groove which is engaged by an annular member K, in which are formed the cams L for moving the chasers into the work.

The chasers M are mounted as before described in radial slots in the member E

and are controlled in position by engagement with the cams. To simplify the construction of these chasers, the thread cutting portion thereof is formed on a rectangular block M' which is secured by a clamping screw N to an L-shaped block O . The inner portion O' of this block is of greater width than the blocks M' and engages a T-shaped groove in the member E to retain the chasers from any movement other than a radial one. The outwardly extending portion O'' of the blocks O are slightly rounded on their outer faces and engage the cams L , which latter are formed by milling into the member K . All of the contacting surfaces are hardened and ground and therefore the wear caused by rubbing contact is comparatively slight. The chasers are yieldably moved outward against the cam by springs P located in recesses in the member E and engaging laterally extending pins Q on the blocks O .

The inward movement of the chasers into working position is effected by rotation of the member K in respect to the shank A and members D , E and F . To secure accuracy in the performance of the work, the inner limit of movement of the chasers must be exactly predetermined and this requires the stopping of the rotation of the member K at an exactly predetermined point. This stopping is effected primarily by a latch pin R slidably engaging a recess in the member F and also engageable with a recess in the member K , into which it is projected by the tension of a spring R' . This will lock the member K from rotation until the pin is disengaged from its locking recess, which is accomplished by the longitudinal separation of the members F and K from each other. The member F is rotatively adjustable in relation to the member D by means of a pair of opposed set-screws S and S' in the member F engaging a pin S^2 projecting radially from the member D . This pin enters a groove S^3 in the inner face of the member F and extending longitudinally thereof, the width of said groove being sufficient to provide for the necessary range of adjustment and the set-screws S and S' locking the pin in different positions of adjustment. Thus the position of the thread-cutting edges of the chasers is determined by the relative angular positions of the head E and cams L on the sleeve K , while the position of the latter member, when locked to the member F by the latch bolt R , is determined by the adjustment of the set-screws S and S' . Therefore, if it is desired to either increase or decrease the finished size of the threaded work, this may be accomplished by adjusting the set-screws S and S' in one direction or the other. The accuracy of this adjustment is, however, dependent upon elimination of any

lost motion in the parts and as the latch pin R is subject to wear, it is obvious that there is danger of loss of accuracy. This I have avoided by making both the pin R and the keeper therefor of renewable parts, so that whenever any lost motion develops, these parts may be replaced to again secure accuracy. In the specific construction shown the keeper R^2 is formed in a segmental block, which is secured in a recess in the member K by a series of screws R^3 and a locking pin R^4 . This block may be exchanged at any time by removing the screws, and the latch pin R may be detached by removing the plate J and slipping it out from the recess. 70 75 80

The chasers are retracted after the completion of the work, first by the longitudinal pull upon the head E which carries with it the member K and separates the latter from the member F so as to release the latch pin R . When thus released, the member K must be revolved to release the pressure of the cams L and this rotation is effected by a spring or springs T . With constructions as heretofore made it is usually necessary to assemble the springs with the other parts and on account of the relatively high tension, this operation is difficult. With my improved construction all of the other parts are first assembled, after which the spring or springs may be inserted and placed under the requisite tension. Specifically, the member K has formed therein the annular recess T forming a 95 100 105 groove for receiving the spring, and an abutment block is placed in this recess in one end of the spring, the other end of which engages an abutment on the member E . Preferably two springs are employed and each of these is inserted into the recess T through a tangential entrance port U . The ports U are closed by screw-threaded plugs U' which also constitute the abutments for the springs. The opposite 110 ends of the springs engage with pins V , which engage radial apertures in the member E and project outward therefrom into the annular recess T . The rotary movement under the tension of the springs is limited 115 by stop blocks W , which are placed in the annular recess T , and these blocks are so arranged as to form complementary parts of the threaded recesses in which the plugs U' are engaged. The stop blocks W are 120 located by pins W' securing the same to the member K .

To avoid breaking of the thread cutters or chasers, due to the impact of the work thereagainst, a yielding cushion is provided. 125 This is formed by springs X placed in recesses in the member D , which bear against the flange B and normally separate said flange and member D . When, however, there is an impact against the head E , the 130

springs X will yield and will cushion the blow.

With the construction as described, it will be understood that the manufacture of the parts comprising the tool is simple and inexpensive, while the assembly of the parts may be quickly accomplished. The order of assembly is to first engage the chasers with the radial slots in the head E, then to place the sleeve K in engagement with said head, and to secure these parts together by an annular front plate Y secured by screws Y'. The pins G being pressed into engagement with the member D and the member F being also engaged with said member D, these parts may then be assembled with the parts E and K and are secured by the bolts H with the springs I sleeved thereon. The springs X are then placed in the recesses in the member D, after which the shank A may be assembled with the other members and secured by the engagement of the plate J. Finally the springs T' are inserted through the tangential ports U to bear against the pins V and the plugs U' are inserted and screwed in to form abutments for said springs.

In operation, the revolving work is fed axially into engagement with the chasers, the shock of first contact being cushioned by the springs X. The threading operation will then continue until completed, whereupon arrest of further inward movement of the work will cause a pull upon the chasers and head E, separating the member K from the member F and disengaging the latch pin R from the keeper block R'. This will permit the springs T' to quickly revolve the sleeve K, thereby withdrawing the cams from the blocks O and permitting the springs P to retract the chasers out of engagement with the work. The chasers are then restored to operative position by rotating the member K until the latch pin R again engages with its keeper.

In Figures 9 and 10 a modified construction is shown which is designed for a threading operation where the tool is revolved and the work is stationary. With this construction the chaser blocks M' are engaged with L-shaped holder blocks M² which have cam portions O³ thereon for engagement with a longitudinally adjustable sleeve member K'. This sleeve member is mounted upon the head E² which has the radial slots for receiving the chasers and which is also attached to the revoluble spindle A'. The members E² and K' are secured to each other against relative rotation by bolts or pins H² having springs I' sleeved thereon and said bolts also secure to the member K' a grooved collar Z. This collar forms a means for adjusting the members Z and K' longitudinally in relation to the members A' and E², while permitting the rotation

of all of said members and such adjustment will effect the radial movement of the chasers by the engagement of the cams O³ with the sleeve member K'. There is also a means of adjustment provided by which the exact size of the finished work may be determined, this consisting in cams L' on the member K' for cooperating with the cams O³ on the chasers and which are adjustable by a relative rotation of the members K' and Z. This relative rotary adjustment is effected by a construction similar to the parts S, S' and S² already described and indicated at S⁴. With this modified construction the operation is substantially the same, with the exception that the work is stationary and the tool is revolved, while the relative longitudinal movement is effected by a suitable fork (not shown) engaging the grooved collar Z.

What I claim as my invention is:

1. In a thread-cutting tool, the combination with a head, radially adjustable chasers carried by said head and a cam member for actuating said chasers rotatable upon said head and provided with an annular recess, of a spring located within said recess between said head and cam for effecting the relative rotation thereof, and means for inserting said spring within said recess and subsequent to the assembly of the other parts.

2. In a thread-cutting tool, the combination with a head and chasers radially adjustable in relation thereto, of a cam for adjusting said chasers rotatable upon said head, said cam and head being constructed to form an annular recess therebetween with an abutment secured to the one projecting into said recess, a spring insertable through a tangential entrance port into said recess into engagement with said abutment, and a closure for said tangential entrance port forming an opposed abutment for said spring.

3. In a thread-cutting tool, the combination with a head and chasers radially adjustable in relation thereto, of a member rotatable upon said head for actuating said chasers radially, said head and rotatable member being constructed to form an annular recess therebetween with a tangential entrance port to said recess, a spring insertable into said recess through said tangential port, and a plug for closing said port and forming an abutment for said spring.

4. In a tool, the combination with a head and a member radially adjustable in relation thereto, of a member rotatable upon said head, said head and member being formed to provide an annular recess therebetween with a tangential entrance port to said recess, a spring insertable into said recess through said tangential entrance port,

130

- 4
- an abutment for said spring secured to one of said members and projecting into said recess, a stop for said abutment within said recess adjacent to said tangential entrance port and forming a complementary portion of the wall thereof, and a screw-threaded plug forming a closure for said tangential port engaging corresponding threads in said port and stop.
5. In a tool, the combination with a head and a cutter member radially adjustable in relation thereto, of a member rotatable on said head, said member and head having formed therebetween, an annular recess with a pair of tangential entrance ports on diametrically opposite sides thereof, springs insertable through said entrance ports into said recess, abutments on one of said members projecting into said recess on diametrically opposite sides thereof and engaging the respective springs, stop blocks for said abutments secured to the other of said members adjacent to said tangential ports and forming complementary portions of the walls thereof, and screw-threaded plugs for closing said ports engaging corresponding threads in the walls thereof and in said stop blocks.
6. In a tool, the combination with a head and a plurality of radially adjustable chaser blocks carried thereby, of a rotary member mounted on said head and having an annular recess in its inner face with a tangential entrance port from the outer face thereof, an abutment pin projecting radially from said head into said recess, a spring insertable in said recess through said entrance port, and a screw-threaded plug for closing said entrance port forming an abutment for said spring, and a means for tensioning the same.
7. A thread-cutting tool comprising a head, chasers radially adjustable thereon, a member rotatable upon said head provided with cams for actuating said chasers towards their working positions, a member rotatively adjustable upon said head adjacent to said rotatable member, an automatically operated catch for holding said rotatable member in predetermined relation to said rotatively adjustable member, and means for adjusting said adjustable member.
8. In a thread-cutting tool, the combination with a head having a chaser guideway therein, of a chaser comprising a rectangular block constituting a cutter, an L-shaped carrier for said block having a relatively wide longitudinal portion for engaging said guideway and an angular portion for engaging the end of said block, and a screw for securing said block and carrier in fixed relation.
9. In a thread-cutting tool, the combination with a head having a chaser guide-way therein of T-shaped form, a chaser for en-
- gaging said guide-way comprising a substantially rectangular cutter block fitting into the stem portion of said T-shaped guide-way, an L-shaped carrier for said block having an inner portion fitting into the head portion of said T-shaped guide-way, and an outer portion for engaging the end of said block, said inner portion having a greater width than said outer portion, and a screw passing through said block and into engagement with said carrier to hold the same in fixed relation.
10. In a thread-cutting tool, the combination with a head having a radial guide-way therein of T-shaped cross section, a chaser for engaging said guide-way comprising a rectangular cutter block for engaging the stem portion of said T-shaped guide-way, and an L-shaped carrier with which said block is detachably engaged, slidably engaging the base of said carrier having a greater width than said cutter block, the head portion on said T-shaped guideway.
11. A thread-cutting tool comprising a shank, a head sleeved upon said shank and provided with radially extending guideways, chasers slidably secured in said guideways, a rotatable member surrounding said head and provided with cams for actuating said chasers in said guideways, a non-rotatable head sleeved on said shank adjacent to said first-mentioned head, a latch for locking said rotatable head in fixed relation to said non-rotatable head, resilient means for holding said heads in contact with each other, permitting the longitudinal adjustment of said rotatable head to disengage the latch therefrom, and means for cushioning the non-rotatable head upon said shank permitting a limited longitudinal movement thereof.
12. A thread-cutting tool comprising a shank, a collar thereon, a head sleeved upon said shank and recessed to receive said collar, a pin extending parallel to said shank, forming a rotative coupling between said head and collar, a head adjacent to said first-mentioned head slidably engaging said pin, a resilient yieldable connection for holding said heads in contact with each other, chasers slidably engaging radial guides in said last-mentioned head, a rotatable member engaging said heads and having cams for actuating said chasers, an annular member surrounding said first-mentioned head adjacent to said rotatable member, a latch for locking said rotatable member and annular member to each other, and means for rotatively adjusting said annular member in relation to said first-mentioned head to exactly predetermine the adjustment of said chasers in working position.
13. In a thread-cutting tool, the combination with a head and chasers radially adjustable in relation thereto, of a member rotatable upon said head for actuating said

chasers radially, an annular member surrounding said head beneath said rotatable member, a spring pressed catch slidably mounted in said annular member for engagement with said rotatable member, and means for adjusting said annular member about said head.

14. In a thread-cutting tool, the combination with a head and chasers radially adjustable in relation thereto, of a member rotatable upon said head for actuating said chasers radially, said head and rotatable member being constructed to form an annular recess therebetween with a tangential entrance port to said recess, a spring insertable into said recess through said tangential entrance port, an abutment on one of said members projecting into said recess, a stop block for said abutment secured to the other of said members, an annular member surrounding said head, a catch carried by said annular member for engagement with said rotatable member, and means for adjusting said annular member about said head.

25 15. In a thread-cutting tool, the combination with a head and chasers radially ad-

justable in relation thereto, of a member rotatable about said head for actuating said chasers radially, an annular member surrounding said head beneath said rotatable member, an automatically operated catch slidably mounted in said annular member for engagement with said rotatable member, and means for adjusting said rotatable member with respect to said head when said catch is disengaged therewith.

16. In a thread-cutting tool, the combination with a head and chasers radially adjustable in relation thereto, of a member rotatable about said head for actuating said chasers, said head and rotatable member being constructed to form an annular recess therebetween with a tangential entrance port to said recess, a spring insertable into said recess through said tangential entrance port, an abutment on one of said members projecting into said recess, and a stop block for said abutment secured to the other of said members.

In testimony whereof I affix my signature.

HARRY T. WHITE.
